COMMUNICATION SYSTEM

Walter S. Lemmon, New York, N. Y., and Clyde J. Fitch, Jersey City, N. J., assignors to International Business Machines Corp., New York, N. Y., a corporation of New York

Application February 10, 1934, Serial No. 710,614

16 Claims. (Cl. 178—4)

The present invention pertains to a novel communication system designed for the sending of messages by electrical impulses and is applicable to radio, carrier current and line trans-

mission, etc.

The invention embodies the use of synchronized disks or distributors at the transmitting and receiving stations for completing the transmitting and receiving circuits respectively similar to the synchronizing system disclosed in the co-pending application Serial No. 684,362 filed August 9, 1933. At the sending station, the impulse is not transmitted until contact of revolving arm is made at the particular contact 10 of the distributor corresponding to the actuated key for the character to be sent; and at the instant of contact, the impulse is sent out and caused to register the same character at the receiving station, due to the synchronism of the 15 contact disks or distributors.

In the present invention the characters are transmitted by the depression of key bars. On depression of a bar, a condenser that has been charged previously is caused to be discharged, 20 and when the bar is released and when the rotary arm of the sending distributor makes contact a circuit including a resistor is completed to charge the condenser; a transmitting circuit connected to the condenser charging circuit 25 is activated, as a result of which an impulse is transmitted. Thus the transmitting apparatus is energized on the return rather than the depression of the bar, in this manner causing the duration of the impulses to be equal 30 and facilitating reception at the rapidly acting receiving mechanism.

The principal object of the invention is to provide an improved method of activating the transmitting circuit relying on the synchronization of parts of the transmitting and receiving apparatus rather than on the duration of the impulses. A further object is to provide an apparatus which may be used interchangeably 40 for sending or receiving.

Various other objects and advantages of my invention will be obvious from the following particular description of one form of mechanism embodying the invention or from an inspection of the accompanying drawing, and the invention also constitutes certain new and novel features of the construction and combination of parts hereinafter set forth and claimed.

The invention is fully disclosed by way of example in the following description and in the accompanying drawing which shows a diagram-

matic view of the apparatus. Inasmuch as the receiving apparatus and sending apparatus are alike, a detailed description of only one of them will suffice.

The transmitting apparatus, (and also the receiving apparatus) includes a conventional or modified typewriter having a series of lettered and numbered pivoted key bars 1. Over the bars is mounted a roll 2 held in a slidable carriage (not shown) in the usual manner so that it is moved one space on depression of any key bar. Each key bar has associated therewith a type bar 3 adapted to strike against the roll 2 on depression of the corresponding key bar. This action is effected through a suitable linkage 4 between each key bar and its corresponding type bar. A sending distributor 5 carries a series of spaced contacts 6 corresponding respectively to the various characters on the type bars 3. The contacts are engaged 20 in rather rapid succession by a rotary contact arm 7 driven by a motor 8, which is in synchronism with the similar device at the other end of the transmission circuit and which is fully described in the co-pending application 25 stated hereinbefore.

Each of the key bars 1 is comprised in a branch condenser circuit; from a contact 9 disposed respectively beneath the key bars, and normally spaced from the latter when the bars 30 are in their normal or raised position, a line 10 is extended separately from each lower contact to individual condensers 11, said condensers in turn connected to a corresponding key bar, so that upon depressing the key bar, its corresponding condenser if charged previously is discharged. Each of the key bars is comprised in a circuit embodying common conductors 12 and 13 extending to rotary arm 7, in which are comprised a sending switch 14 closed at the sending 40 end, resistor 15, and condenser charging battery 16. The corresponding switch is open at the receiving end, as will be more fully described hereinafter. From the distributor contacts 6 conductors 17 extend separately to fixed contacts 18 positioned over the key bars. The latter contacts are engaged by the corresponding bars 1 when the latter are in raised or released position and at such time close a corresponding condenser charging circuit consisting of said 50 bar 1 and contact 18, contact 6, rotary arm 7, conductor 13, battery 16, resistor 15, switch 14, conductor 12 and corresponding condenser 11. Thus when any of the bars 1 is depressed, the corresponding condenser 11 will be short cir- 55

- cuted and discharged through the bar engaging contact 9 and conductor 10. A sending circuit is connected to the terminals of resistor 15 and comprises the usual transmitting means.
- 5 The transmitter 20 as shown has one of its output terminals connected to an antenna 21 and its other output terminal 22 grounded in the usual manner. As mentioned previously this invention is applicable to radio, carrier current 10 and line transmission, for this purpose a transmission line 21a is shown connecting the stations.
- 15 In the operation of the device as thus far described, it will be seen that the depression of a key bar 1 first breaks its condenser charging circuit to short circuit and discharge the condenser 11. On the return of the bar it engages its corresponding upper contact 18 and when the rotary arm engages its contact 6 corresponding to the depressed key bar, the condenser charging circuit is completed, so that the drop across resistor 15 caused by charging current pulse activates the connected sending circuit 19 and transmitting apparatus 20, as a result of 20 which an impulse is transmitted.
- 25 In order to insure correct operation of the transmitting system upon starting, the normally closed switch 40 included in the input circuit to the radio or line transmitter is opened until 30 the individual condensers 11, which may have been discharged by leakage, are fully charged by having all the distributor contacts 6 engaged successively by the rotary arm 7 in a manner described above, and in this manner prevent operation of the receiving system which will now 35 be explained.
- 30 The receiving circuit of each apparatus includes a receiver 23 having one of its input terminals grounded at 24 and its other input terminal connected to an antenna 25 or line 21a 40 to receive the impulse sent out from transmitter 20 in the usual manner.
- 35 Beneath each of the key bars 1 is a solenoid 26 adapted to operate on a plunger 27 depending from the bar, so that when a given solenoid is 45 energized by the means presently to be described, the corresponding key bar will be depressed to actuate the corresponding type lever 3. The receiving circuit is governed by a receiving distributor 28 carrying elongated spaced contacts 50 29 corresponding in number and position to contacts 6 on sending distributor 5.
- 55 The contacts 29 are of greater length circumferentially than contacts 6 so as to hold the receiving circuit closed for an interval sufficient to enable energization of the solenoids 26 and operation of the type bars 3 as well as to allow for slight inaccuracies in the synchronism of the 60 rotary arms 7 and 30 respectively. The rotary arm 30 wipes over the contacts 29 and is driven by a motor 31 and rotates in synchronism with rotary arm 7 as previously disclosed, so that the arms of both distributors are in engagement with similarly identified contacts at any instant.
- 65 The contacts 29 are connected separately to its corresponding solenoid 26 by lines 32. A common conductor 33 extends from one of the output terminals of receiver 23 to the remaining terminals of the solenoids. The other output terminal of the receiver is connected by conductor 34 to battery 35, the other side of the battery is extended to rotary arm 30 by line 36 including switch 37.
- 70 On reception of an impulse at the receiver 23, the receiving circuit is energized instantaneously and includes conductor 34, battery 35, conductor 36, switch 37, rotary arm 30, any contact 29 and the particular conductor 32 and solenoid 26 corresponding to the contact 29 engaged by arm 30, and conductor 33 back to receiver 23. Upon completion of said circuit the particular said solenoid is energized causing the character corresponding to the contact 29 to be printed on the roll 2. The characters printed will appear in the same order in which they are sent inasmuch as 10 the said arms 7 and 30 are always in like relationship to the contacts engaged thereby due to their synchronous rotation.
- 15 In order to bring the sending rotary arm 7 into register with receiving arm 30, with respect to the contacts of distributors 5 and 28, the sending operator first transmits a predetermined signal for a given interval, whereupon the receiving operator sets the arm 30 on a given contact 29 corresponding to the predetermined position of 20 the arm 7 on the sending distributor.
- 20 It will be evident that the switch 14 being open at the receiving end renders the condensers 11 inoperative and ineffective, and in like manner the receiving switch 37 being open at the sending end, renders the receiving circuit inoperative. Thus the apparatus installed at any station may be used interchangeably for sending or receiving on proper adjustment of the said 25 switches.
- 25 While there has been shown and described and pointed out the fundamental novel features of the invention as applied to a single modification, it will be understood that various omissions and substitutions and changes in the form and details of the device illustrated and in its operation may be made by those skilled in the art 30 without departing from the spirit of the invention. It is the intention therefore to be limited only as indicated by the scope of the following 35 claims.
- 35 What is claimed is as follows:
1. In a communication system, capacitive reactance devices corresponding to characters to be transmitted, means to supply current to said devices, means for initiating transmission of signals corresponding to said characters, and means to effect transmission of initiated character signals upon supplying current to said devices.
- 40 2. In a communication system, means for initiating transmission of character signals, a plurality of charge accumulating devices corresponding to characters to be transmitted, means under control of initiating means for charging said devices, and means to transmit initiated character signals upon charging of said devices.
- 45 3. In a communication system, a plurality of elements for initiating character signals, means cooperating with said elements to supply energy for transmission of character signals, means under control of said initiating means for energizing first named means, and means for effecting energization of first named means to cause transmission of initiated character signals upon energization of first named means.
- 50 4. In a communication system, a plurality of condensers, one corresponding to each character to be transmitted, means for charging said condenser, a mechanism for initiating transmission of signals corresponding to the different characters and means under control of initiating means for effecting charging of the different condensers at differential times in accordance with the different characters to be transmitted.

5. A signal controlling circuit having a source of current supply, an element for initiating flow of current from said supply through the circuit, a condenser in the circuit charged by the flow 5 of current upon operation of said initiating element to vary the circuit characteristics, and means controlled by the circuit by and upon variation of the current characteristics to transmit a signal.
10. 6. In a communication system, a sending machine having charge accumulating devices, means for initiating transmission of signals, circuits for energizing said devices upon operation of said initiating means, and a transmission circuit connected to the first named circuits and activated upon energization of the said devices.
15. 7. In a communication system, a sending machine, having capacitive reactance elements, key bars, each associated with a reactance element, circuits operated by the corresponding key bars for energizing said elements upon operation of said key bars, and a transmission circuit connected to the first named circuits and activated upon energization of the corresponding 20 reactance elements.
25. 8. In a communication system, a sending machine having capacitive reactance elements, key bars, each associated with a reactance element, circuits operated by the corresponding key bars for energizing said elements upon operation of the key bars, a transmission circuit connected to the first named circuits, and means associated with the first named circuits to activate said transmission circuit upon energization of the 25 corresponding reactance elements.
30. 9. In a communication system, a sending machine having capacitive reactance elements, key bars, each associated with a reactance element, circuits operated by the corresponding key bars for energizing said elements upon operation of the key bars, a transmission circuit connected to the first named circuits, and electrical impeding means associated with the first named circuits to activate said transmission circuit upon energization of the reactance elements.
35. 10. In a communication system, a sending machine having key bars, a condenser for each bar, contact members corresponding to said bars and connected respectively to said condensers to receive the charging current for said condensers 40 respectively upon operation of said bars, and a transmission circuit to be energized by the flow of charging current through said contacts to said condensers.
45. 11. In a communication system, a sending machine having key bars, condensers for each key bar, circuits for charging said condensers, the key bars operable for initiating operation of its corresponding circuit, contact members corresponding to said bars and connected respectively to said condensers to receive charging current for said condensers, a transmission circuit connected to the first named circuits to be energized by said condenser charging current, and means 50 associated with said contact members to complete the operation of the first named circuits to charge the condensers and to cause the energization of said transmission circuit.
55. 12. In a communication system, a sending machine having capacitive reactance elements, depressible key bars, circuits for energizing said elements upon return movement of the key bars, and a transmission circuit connected to the first named circuits and activated upon energization 55 of the reactance elements.
60. 13. In a communication system, a sending machine having capacitive reactance elements, depressible key bars, each associated with a reactance element, circuits operated by the corresponding key bars for energizing said elements upon return movement of the key bars, a transmission circuit connected to the first named circuits, and means associated with the first named circuits to activate said transmission circuit upon energization of the corresponding reactance elements.
65. 14. In a communication system, a sending machine having key bars, a condenser for each key bar, circuits operated by the corresponding key bars for charging said condensers upon return movement of the key bars, a transmission circuit connected to the first named circuits, and a common resistor connected to the first named circuits to energize said transmission circuit upon the charging of the condensers.
70. 15. In a communication system, a sending machine having key bars, a condenser for each key bar, circuits operable by the key bars for charging its corresponding condenser upon return movement of the key bars, a resistor connected to said circuits, a transmission circuit connected to the first named circuits to be energized upon flow of the charging current through the resistor, a receiving circuit sensitive to the transmission 75 circuit, printing members associated with said key bars, electrical devices in said receiving circuit for operating said key bars and printing members, and a selecting switch for rendering either said receiving circuit or said condensers, 45 inoperative and rendering the other operative.
75. 16. In a communicating system, a printing machine having key bars, a condenser for each key bar, circuits operable by the key bars for charging its corresponding condenser upon return movement of the key bars, a resistor connected to said circuits, a transmission circuit connected to the first named circuits to be energized upon flow of the charging current through the resistor, a receiving circuit, printing members associated with said key bars, electrical devices in said receiving circuit for selectively operating said key bars and printing members, and a selecting switch for permanently rendering either said receiving circuit or said condenser circuit inoperative and rendering the other operative.
